Primary Examiner—Ruth McInroy*(74) Attorney, Agent, or Firm*—Nixon & Vanderhye**(57) CLAIM**

The ornamental design for a vacuum cleaner, as shown and described.

DESCRIPTION

FIG. 1 is a top, front and left side perspective view of a vacuum cleaner showing my new design;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof;
 FIG. 7 is a bottom plan view thereof;
 FIG. 8 is a top, rear and left side perspective view thereof;
 FIG. 9 is a top, front and left side perspective view of a vacuum cleaner of a second embodiment thereof;
 FIG. 10 is a front elevational view thereof;
 FIG. 11 is a rear elevational view thereof;
 FIG. 12 is a right side elevational view thereof;
 FIG. 13 is a left side elevational view thereof;
 FIG. 14 is a top plan view thereof;
 FIG. 15 is a bottom plan view thereof;
 FIG. 16 is a top, rear and right side perspective view thereof;
 FIG. 17 is a top, front and left side perspective view of a third embodiment thereof;
 FIG. 18 is a front elevational view thereof;
 FIG. 19 is a top plan view thereof;
 FIG. 20 is a right side elevational view thereof;
 FIG. 21 is a left side elevational view thereof;
 FIG. 22 is a top plan view thereof; and,
 FIG. 23 is a bottom plan view thereof.
